THOMAS MARVIN, OF MIDDLESEX COUNTY, MASSACHUSETTS.

Letters Patent No. 77,745, dated May 12, 1868.

IMPROVEMENT IN ATTACHING DOOR-KNOBS TO SPINDLES.

The Drawing referred to in these Letters Patent and making part of the same.

TO ALL WHOM IT MAY CONCERN:

Be it known that I, THOMAS MARVIN, of the county of Middlesex, and State of Massachusetts, have invented an Improvement in Door-Knobs and Spindles; and I do hereby declare that the following, taken in connection with the drawings which accompany and form part of this specification, is a description of my invention sufficient to enable those skilled in the art to practise it.

The invention relates to the manner of fastening door-knobs upon spindles, with a view to dispense with the pin usually driven through the handle and spindle to hold them together. The use of this pin is objectionable, because it is unsightly, because it is continually dropping out of place, and because its use involves the necessity of adjusting the length of the spindle or the point at which it is to be bored, in accordance with the thickness of the door to which the knobs are to be applied.

In my invention I use, in connection with each knob, a spindle-socket, having a journal or cylindric surface, upon which the escutcheon fits, with a flange at the end of such socket to keep the handle from being drawn from the escutcheon, the escutcheon being made to be screwed upon the door, and having also a shoulder, upon which a disk, applied to the inner end of the knob, fits, this disk being confined to the knob by turning a peripheral flange back and down upon the neck of the knob. The shank of the socket-piece is square in section, and fits into a knob-mortise, which is made square, to receive it, and to cause it to turn with and only with the knob. The spindle is confined to the socket-piece of one knob by a suitable pin passing only through the socket and spindle, and the opposite end of the spindle slides freely in its knob-socket, it being confined in position relative thereto, when the knobs are applied, by the confinement of the two escutcheon-plates to the opposite surfaces of the door.

It is this construction that constitutes my invention, and the drawing represents a sectional view of the two knobs and spindle.

a denotes the spindle; *b b'*, the knobs, the spindle being confined to knob *b*. *c c'* denote the escutcheons, each provided with holes, *d*, for entrance of screws to fasten them to the door-faces. Each of these escutcheons has a central bearing or circular hole, *f*, for supporting the spindle-socket piece *g*, which has a square mortise, *o*, for receiving the square spindle, and on its outer surface a cylindrical shoulder, *h*, which fits into the escutcheon-bearing *f*, and rotates therein, the socket-piece having a lip or flange, *i*, against which the inner surface of the escutcheon rests, and the shoulder *h* being of a width corresponding to the thickness of the escutcheon, as seen in the drawing. At the outer end of the shoulder *h* is a metal disk or plate, *i'*, which slips upon the socket-piece *g*, which may rest upon a shoulder, *k*, thereof, and this disk may be brazed or soldered to the socket-piece, and be thereby fixed relatively thereto.

The outer surface of the shank of the socket-piece *g* is preferably made square in section, and the mortise *x*, in the knob, also has this form, to insure the rotation of the spindle, by rotation of the handle, and each disk, *i'*, has at its outer edge a peripheral flange, *l*, which is turned down upon the handle-neck, as seen in the drawing, and the turning over of this flange secures the knob to the disk, and thereby to the spindle-socket piece. The spindle slides in each socket-piece; or is made capable of such movement, though to one end of the spindle it is preferably confined by a pin, *m*, passing through the spindle and socket-piece.

The spindle and the socket in one knob are made of such length and depth as will enable the knobs to be applied to doors of all thicknesses.

When the knobs are to be applied to a door, the spindle is thrust through the door, and the escutcheon *c* is screwed to the face thereof. This attaches the spindle and knob *b*. The knob *b'* is then slid upon the opposite end of the spindle, and the escutcheon *c'* is screwed to the door, and this not only confines the knob *b'* to the door, but to the spindle, so that by turning either knob, the latch is operated in the usual manner.

As in turning the knob, the cylinder *h* turns in the escutcheon, and as this bearing is of much larger diameter than the spindle, it will readily be seen that the knob is kept from sagging and from loosening, the lip *i* holding the socket-piece steadily in position, and as there is no pin connecting the spindle and handle, the handle cannot become loose or detached by wear of this pin, or by its dropping from its place.

I claim the combination of the stationary escutcheons, the spindle, the spindle-sockets, with the shoulder *h* and flange *i*, the disks and the knobs, when constructed, connected, and relatively arranged, substantially as described.

THOMAS MARVIN.
